UNITED STATES PATENT OFFICE

144,466

DESIGN FOR A LADY'S COAT OR SIMILAR ARTICLE

Jeanne Miller, Vermilion, Ohio

Application July 23, 1945, Serial No. 120,876

Term of patent 14 years

(Cl. D3—4)

To all whom it may concern:

Be it known that I, Jeanne Miller, a citizen of the United States of America, residing in the city of Vermilion, county of Erie, and State of Ohio, have invented a new, original, and ornamental Design for a Lady's Coat or Similar Article, of which the following is a specification, reference being had to the accompanying drawings, forming part thereof.

Figure 1 is a front elevational view of a lady's coat showing my new design; Figure 2 is a rear elevational view of the coat seen in Figure 1;

Figure 3 is a fragmentary side elevational view of the coat seen in Figure 4; Figure 4 is a fragmentary front elevational view corresponding to Figure 1 but showing the position the parts take when the arms of the wearer are raised; Figure 5 is a fragmentary rear elevational view of Figure 4; Figure 6 is a fragmentary side elevational view of Figure 1.

I claim:

The ornamental design for a lady's coat or similar article, as shown.

JEANNE MILLER.
